RAILWAY DUMP CAR DOOR OPERATING
MECHANISM

William F. Batho, Chicago, Ill., assignor to Enterprise Railway Equipment Company, Chicago, Ill., a corporation of Illinois

Application June 17, 1943, Serial No. 491,180

5 Claims. (Cl. 105—300)

My invention relates to improvement in dump car door operating mechanisms, and is especially related to that general type of door operating mechanism having a bodily movable and rotatable shaft adapted to travel from a position beyond the free edge of the door to a supporting position beneath the free edge thereof.

In this type of car a single shaft is arranged to operate a plurality of doors and each door is connected with the shaft by flexible connections, such as pivotally connected links or chains, which wind around the shaft to close the door. It frequently occurs that some of the doors controlled by the shaft are held closed either by freezing or by intentional propping up, in which event the flexible connections associated with the closed doors do not properly unwind with the rotation of the shaft, but instead pile up or jam against the underside of the car sills and frame and interfere with the rotation of the shaft.

The principal object of my invention is to overcome this tendency to jam or pile up by the provision of means which causes the flexible chains to properly unwind even though the door is held in closed position.

Another object of the invention is to improve the winding connections for the doors to adapt them to the practice of deliberately propping up in closed position some of the doors operated by the shaft, this practice being employed where it is desired to discharge the car load through a lesser number of doors.

With these and other objects of the invention, my invention consists in the construction, combination and arrangement of parts hereinafter described in connection with the accompanying drawings which illustrate one embodiment of the invention.

Referring to the accompanying drawings,

Fig. 1 is a vertical transverse section through one half of the underframe of a car, and showing one of the dump doors and the shaft and flexible connections associated therewith for opening and closing the door;

Fig. 2 is an enlarged view of the door operating parts shown in Fig. 1;

Fig. 3 is a view similar to Fig. 2, taken on the line 3—3 of Fig. 5 but showing the shaft bodily moved to the outer position from beneath the free edge of the door and about to start the unwinding of the flexible connections;

Fig. 4 is another similar view showing the unwinding of the flexible connections with the door in closed position;

Fig. 5 is a transverse horizontal section substantially on the line 5—5 of Fig. 3; and

Fig. 6 is a view illustrating the flexible connections completely unwound, but with the door in closed position.

In the drawings I have shown a door operating mechanism especially adapted for cars of the drop-bottom door type, which have a plurality of doors on each side of the center sill operated from the ends of the car through the medium of a shaft which extends longitudinally of the car and just underneath the car side sills. In cars of this type, each shaft is arranged to operate several doors simultaneously, but in the drawings I have illustrated only one of the winding mechanisms operated by the shaft for opening and closing the doors.

The car as shown has a center sill A, crossbeams 1, and side sills 2. Discharge openings are thus provided between the center and side sills and the crossbeams which are closed by flat doors B which bear at their margins against the under side of the cover plates on the center sills and crossbeams, and on the under side of the side sills. The doors are hinged at 3 at their inner margins adjacent the center sill, and are adapted to swing about these hinges to open or closed positions. The doors are reinforced by downwardly extending marginal flanges 4.

The operating shaft C is mounted in bearing castings 5 which are secured to and supported by the crossbeams 1. These bearings are formed as elongated slots 6 which permit of a bodily movement of the shaft upon rotation in a generally horizontal direction so that the shaft moves bodily upon rotation into or out of door-supporting position. The shaft is connected with the door by flexible connections forming winding mechanisms which swing the door to open or closed positions. Generally two of these winding mechanisms are provided for each door which the shaft serves. In the drawings, however, only one of these mechanisms is shown in detail since the others are duplicates thereof.

Each of these winding mechanisms includes four links 7, 8, 9, and 10, which are adapted to wind about a hub member 11 on the shaft when the door is swung to closed position and to unwind from said hub when the door is lowered to open position. The links 8 and 10 are formed as single members and the links 7 and 9 are each formed of two members spaced apart. The ends of links 8 and 10 are positioned between the members which form the links 7 and 9. These links are pivotally connected to each other by means of

the rivets 12, as is usual in this type of flexible operating connections.

The end of the link 7 is pivotally connected by means of a rivet 13 to an arm 15 on the operating hub 11. The end of the link 10 is pivotally connected by means of the rivet 16 to the other end of a door supporting link D which is formed of two spaced apart members 17. The other ends of link D members 17 are pivotally mounted on a rivet 18 which is supported by the walls 19 of an inverted boxlike casting 20 which is fastened to the underside of the door between its outer flange 4 and a Z-shaped angle reinforcement member 21 extending parallel to the flange 4. The link D extends through a notch in the flange 4 of the door and has flat bearing surfaces 22 upon which the flange notch is supported. The outer end of this link extends outwardly beyond the flange 4 of the door in position to rest upon and be supported by bearing lugs 23 on the hub 11 when the shaft is in normal locking position at the inner ends of its bearing slots, as shown more clearly in Fig. 2. The end link 10 has laterally projecting lugs 24 which are adapted to be engaged by the lugs 25 on the hub member 11 upon the continued rotation of the shaft after the shaft has receded to the outer ends of its bearing slots to apply a positive force directly to the supporting link D to swing the link downwardly and start the unwinding of the link connections.

In the closed position of the door, the parts are in the position shown in Figs. 1 and 2. In this position the shaft is in the inner end of its bearing slots beneath the outer end of link D, thus supporting the door in closed position through the medium of the link D. In order to open the door, the rotation of the shaft in a clockwise direction causes the shaft to be moved bodily outwardly in its bearing slots until it reaches the ends of such slots, whereupon the lugs 24 engage the lugs 25 and force the door supporting link D downwardly. Since the door is supported by the link D, it likewise will move downwardly with the link, and as the links unwind from the hub of the shaft the door will be lowered to its open position. If, however, the door is frozen closed or is intentionally propped in closed position, the link D will swing downwardly about its pivot 18 independently of the door, as shown in Fig. 3, and allow the other links 7, 8, 9 and 10 to hang downwardly in a looped condition and cannot become jammed or interfere with the rotation of the operating shaft.

It frequently happens in cars of this type that one or more of the doors operated by a common shaft are frozen in closed position, while the other doors controlled by said shaft will open normally. It is also desirable at times to open only one or two of the doors controlled by a common shaft. In this case, the remaining doors are intentionally held in closed position by props which are placed against the doors. The advantage of my invention, and particularly the pivoted link connection D with the door, is that under these conditions the winding mechanisms of the doors which are held closed will unwind normally and hang downwardly in loops, as shown in Fig. 6, and not interfere with the rotation of the shaft or the operation of the winding mechanisms which are connected with the doors that are being opened. This is due to the fact that the link D is hinged or pivoted at an appreciable distance inwardly from the free edge of the door, thus enabling it to swing downwardly independently of the door in the event the door is held closed and provide

sufficient clearance between itself and the shaft to allow the other links of the connection to unwind downwardly in a loop.

The bearing surfaces 22 on link D provide an adjustment for regulating the tightness with which the door closes against the margins of the discharge opening. By grinding off the lug surfaces or adding metal thereon by welding, the tightness of the door closure can be adjusted as desired.

I claim:

1. In a dump car of the type having a plurality of bottom discharge doors operated by a common shaft adapted to move bodily from a position beneath the free edge of the door, a door operating mechanism comprising a flexible connection connected at one end to the shaft and adapted to wind around the shaft, and a door supporting member hinged to the under side of the door adjacent its free edge and extending beyond the free edge of the door to rest upon said shaft and adapted when the shaft is moved bodily to swing downwardly independently of the door when the door is otherwise held in closed position, said flexible connection being connected at its other end to said door supporting member.
2. In a dump car of the type having a plurality of bottom discharge doors operated by a common shaft adapted to move bodily to and from a door supporting position beneath the free edge of the door, the combination of a door supporting member hinged at one end to the door adjacent its free edge and extending with its other end beyond the free edge of the door to rest upon said shaft and support the door in closed position, said door supporting member being adapted to swing downwardly on its hinge independently of the door in the event of the door being held closed, and a flexible winding connection connected at one end to the shaft and adapted to wind upon and unwind from said shaft, and having its other end connected to the extended end of said door supporting member.
3. In a door operating mechanism for dump cars of the type having a plurality of bottom discharge doors operated by a common mechanism, comprising a rotatable shaft bodily movable to and from a position beneath the free edges of the doors, a plurality of links forming a flexible connection adapted to wind upon the shaft to close the door, and a door supporting member pivotally mounted at one end on the underside of the door adjacent its edge and having its other end extending beyond the edge of the door and pivotally connected to the end of said flexible connection, said pivotally mounted member having its extended end adapted to rest upon the shaft to support the door in closed position and adapted to be swung downwardly independently of the door in the event the door is held in closed position and adapted to cause the flexible connection to loop downwardly and hang free of the shaft as it is unwound therefrom.
4. In a dump car of the class described, the combination of a car body having a bottom discharge opening, a door for said opening adapted to swing downwardly, an operating shaft mounted to shift bodily to and from a position beneath the edge of the door, and a flexible connection comprising a series of pivotal links connected with said shaft and with said door and adapted to wind upon and unwind from the shaft in the closing and opening operation of the door, said flexible connection including an end link pivotally connected to the underside of the door in-

wardly of the free edge thereof and extending beyond the edge of the door to rest upon the shaft and support the door in closed position, said end link being adapted to swing downwardly independently of the door in the event the door is held in closed position and to thereby cause the links of the flexible connection to hang downwardly in a loop free of the shaft as they are unwound from the shaft.

5. In a dump car of the class described, the combination of a car body having a bottom discharge opening, a door for said opening adapted to swing downwardly, an operating shaft mounted to shift bodily to and from a position beneath the edge of the door, and a flexible connection comprising a series of pivotal links connected with said shaft and with said door and adapted to wind upon and unwind from the shaft in the

closing and opening operation of the door, said flexible connection including an end link pivotally connected to the underside of the door adjacent the free edge thereof and extending beyond the edge of the door to rest upon the shaft and support the door in closed position, said end link being adapted when the shaft is bodily shifted from beneath said link to swing downwardly independently of the door in the event the door is held in closed position and to thereby cause the links of the flexible connection to hang downwardly in a loop free of the shaft as they are unwound from the shaft, said end link having an adjustable bearing portion upon which the margin of the door rests for regulating the tightness of the door in closed position.

WILLIAM F. BATHO.
